UNITED STATES PATENT OFFICE

131,627

DESIGN FOR A GAME BOARD

Otto Hammer, Whittier, Calif.

Application May 31, 1941, Serial No. 101,242

Term of patent 7 years

To all whom it may concern:

Be it known that I, Otto Hammer, a citizen of the United States, residing at Whittier, in the county of Los Angeles and State of California, have invented a new, original, and ornamental Design for a Game Board, of which the following is a specification, reference being had to the accompanying drawing, forming part thereof.

The figure is a plan view of the game board embodying my new design.

The game board has no appreciable or substantial thickness.

I claim:

The ornamental design for a game board, as shown and described.

OTTO HAMMER.
